UNITED STATES PATENT OFFICE.

JOHN C. BOGART, OF BAY CITY, MICHIGAN, ASSIGNOR OF ONE-HALF TO PAUL R. DINSMORE, OF BAY CITY, MICHIGAN.

DIFFERENTIAL GEARING.

1,351,737.

Specification of Letters Patent. Patented Sept. 7, 1920.

Application filed November 15, 1918. Serial No. 262,681.

To all whom it may concern:

Be it known that I, JOHN C. BOGART, a citizen of the United States of America, residing at Bay City, in the county of Bay 5 and State of Michigan, have invented certain new and useful Improvements in Differential Gearing, of which the following is a specification.

This invention relates to differential gearing for motor vehicles and the like, and more particularly to the differential which provides for one drive wheel traveling at a different speed than the opposite drive wheel.

One object of the invention is to impart a positive drive or movement to both drive wheels, and yet admit of the outer wheel traveling faster than the inner wheel when the vehicle is turning a corner.

With the above and other objects in view, the present invention consists in the combination and arrangement of parts, herein-after more fully described, illustrated in the accompanying drawings, and more particularly pointed out in the appended claims, it being understood that changes may be made in the size, proportion and minor details without departing from the spirit, or sacrificing any of the advantages of the invention.

In the drawings:

Figure 1 is a front view of a differential gearing embodying my invention.

Fig. 2 is a side view thereof.

Fig. 3 is a sectional view taken on the line B—B of Fig. 1.

Fig. 4 is also a section taken on the line D—D of Fig. 2.

Fig. 5 is an enlarged detail showing the parts in different positions, and

Fig. 6 is a sectional detail.

Referring now more particularly to the drawings. The numeral 1 indicates the drive shafts of the drive axles of any motor vehicle. A short shaft 2 is interposed between the inner ends, and is in line with the drive shafts 1. This short shaft 2 receives a drive gear 3 which is supported thereon, and which may be of any suitable type such as is adapted to receive the driving force of the motor or other power plant

through suitable power transmitting means commonly used, but not being illustrated in connection herewith.

A flat disk or plate 4, recessed as shown 55 in Figs. 5 and 6 is disposed at each side of the drive gear 3, and is keyed or otherwise suitably secured on the short shaft 2. One or more forked levers 5 are pivoted to each of the plates 4 by means of suitable 60 pivot fastenings 6, and each of the forks have mounted thereon a small roller member indicated by the numerals 7 and 7^a, which are adapted to roll on the surface 8 of the recessed portion 9 of the plate, the opposite 65 end of the lever being provided with an opening adapted to receive the end of a bolt member 10 which is secured to the drive gear 3, and which is actuated thereby.

Ratchet elements are located on one side 70 of each plate 4, and are keyed or otherwise suitably secured to the drive shaft 1 so as to rotate therewith. Each of these ratchet elements comprises a flat disk or plate 11 formed with a lateral flange 12 which is internally toothed as indicated at 13, and having a hub 14 which receives the contiguous ends of the drive shafts 1 and 2, thereby holding them in line.

Arcuate slots 15 are formed in the plates 80 4 near the outer edge thereof, and in which are adapted to operate the pin members 16, carried by the drive wheel 3 and which project laterally therefrom. Pivoted to the recessed portion of the plate members 4 are 85 the dog members 17 and 17^a, extending in opposite directions and adapted to engage the teeth 13 of the plates 11.

Pockets 18 are formed in the surface 19 of the disks or plates 4, and in which are 90 disposed to be seated one end of the expandable helical springs 20, said springs being interposed between the pockets 18 and the underside of the dogs 17 and 17^a to normally hold the said dogs in a given position and 95 admit of their yielding, so that the ratchet elements on one of the plates may travel faster than the ratchet elements on the other plate when the vehicle is turning a corner.

The internally toothed flange 12 of the 100 member 11, faces inwardly over the plate 4, and is engaged by the outer ends of the

spring actuated dogs 17 and 17^a, and when movement of the pin member 10 causes the lever 5 to rock on its pivot 6, and the rollers 7 and 7^a move to the right, one of the dogs 5 is disengaged from the teeth 13 by the action of the roller thereon, while the opposite roller rolls off the opposite dog member and allows it to spring into engagement with the teeth 13, the movement of the lever 5 being so timed that when one of the dogs 10 springs into engagement with the teeth 13, the pin 16 will have traveled to one end of the arcuate slot 15, and will thus impart motion to the plate member 4, which in turn 15 transmits it to the toothed disk member 11 and hence to the drive wheels.

A suitable housing incloses the center of the drive wheel, the plates 4, the ratchet elements mounted thereon, together with the 20 internally toothed disks 11, and is composed of two parts, consisting of the disks 21 having inwardly extending rims or flanges 22, and hubs to receive the ends of the shafts 1. These disks are spaced apart by suitable 25 spacers 23 and are connected by bolts or other fastenings 24.

From the foregoing description it will be readily understood that while both drive wheels are positively rotated, still one wheel 30 may rotate faster than the other, as is necessary when a vehicle is turning.

When power is applied to the drive gear to rotate the same in an anti-clock-wise direction, the dogs and lever 5 assume the position 35 —A— as shown in dotted lines in Fig. 5, the pin 10 moving to the left, rocking the lever 5 on its pivot, the roller 7 then rolls off and away from the dog member 17, thereby releasing same and allowing it to be sprung 40 into engagement with the teeth 13 of the member 11, the opposite roller 7^a also moving to the right and on the dog member 17^a, thus forcing it down and out of engagement 45 with the teeth 13, where it is held until the lever 5 is again actuated. Simultaneously with the movement of the lever 5 and the rollers carried thereby, the pin member 16 travels to the left hand end of the arcuate slot 15 and imparts motion to the plates 4. 50 When the drive gear 3 is rotated in a clockwise direction the parts assume the position as indicated at —B— in Fig. 5.

From the foregoing description it will be obvious that I have perfected a new and inexpensive differential gearing, which provides a positive drive for both wheels of a motor vehicle, and which will also permit of one wheel traveling faster than the other when required.

60 Claims:

1. In a differential gearing the combination of opposite drive shafts, a drive gear disposed between the drive shafts, driving elements located at opposite sides of the

drive gear and having a limited movement 65 independent of the same, ratchet elements mounted on the drive shafts, opposite dogs carried by the driving elements and arranged to engage the ratchet elements, and shiftable means operating between the dogs 70 and connected with and actuated by the drive gear for moving one dog out of engagement with each ratchet element and for permitting another dog to engage the same.

2. In a differential gearing the combination 75 of opposite drive shafts, a drive gear disposed between the drive shafts, driving elements located at opposite sides of the drive gear and having a limited movement independent of the same, ratchet elements 80 mounted on the drive shafts, opposite dogs carried by the driving elements and arranged to engage the ratchet elements, and pivoted shiftable levers operating between the dogs and connected with and actuated 85 by the drive gear and provided at their outer ends with opposite arms having anti-friction devices arranged to engage the dogs to move one dog out of engagement with each of the ratchet elements and permit another dog to engage the same.

3. In a differential gearing the combination 90 of opposite drive shafts, a drive gear disposed between the drive shafts, driving elements located at opposite sides of the 95 drive gear and having a limited movement independent of the same, ratchet elements mounted on the drive shafts, opposite dogs carried by the driving elements and arranged to engage the ratchet elements, pivotally mounted levers operating between the dogs and provided at their outer ends with 100 means for controlling the same and having forked inner ends and means carried by the drive gear for engaging the forked ends of the levers to shift the latter.

4. In a differential drive gear, the combination 105 of opposite drive shafts, a drive gear disposed between the shafts, drive disks located at opposite sides of the drive gear and having a limited movement independently thereof and provided with peripheral recesses, spring actuated dogs mounted on the drive disks and arranged in pairs, ratchet elements carried by the drive shafts 110 and arranged to be engaged by the dogs, and shiftable levers located between the dogs and having rollers operating in the said recesses of the drive disks and arranged to engage the dogs for controlling the same, 115 said levers being connected with and actuated by the said drive gear.

5. In differential gearing the combination 120 of opposite drive shafts, a short intermediate shaft disposed between the drive shafts, 125 a drive gear mounted on the intermediate shaft, drive disks arranged on the intermediate shaft at opposite sides of the drive

gear, said drive gear and disks having a slot and pin connection to permit a limited independent movement of the disks with relation to the drive gear, ratchet wheels 5 mounted on the drive shafts, dogs arranged in pairs and carried by the drive disks for engaging the ratchet wheels and levers piv-

otally mounted on the drive disks and operating between the members of each pair of dogs and provided with means for controlling the same, said levers being connected with and actuated by the drive gear. 10

In testimony whereof I affix my signature.
JOHN C. BOGART.
